TEMPERATURE CONTROL SYSTEM

Lloyd L. Young and James L. Finch, Patchogue,
N. Y., assignors to Radio Corporation of
America, a corporation of Delaware

Application October 15, 1931, Serial No. 568,962

7 Claims. (Cl. 219—19)

This invention relates to a method of, and apparatus for regulating the temperature of frequency control devices, and has especial reference to apparatus for controlling the temperature of a piezo-electric crystal resonator.

One of the objects of the present invention is to provide an improved method of controlling the frequency of a piezo-electric crystal resonator.

Piezo-electric crystals are frequently employed in radio signal transmitters for controlling the frequency of high frequency oscillators. It has been found that these crystals, in order to function properly, must be maintained at substantially constant temperature. Heretofore it has been customary in order to control the temperature of the piezo-electric crystal to enclose the crystal in a receptacle and to regulate the temperature of the air within the container. In such case, the heat liberated by the crystal resonator while vibrating is conducted to the walls of the receptacle through the medium of the air within the container. Since air is a poor conductor of heat it has been found that the crystal, frequently, is at a much higher temperature than the receptacle. Conversely, when the receptacle is heated by a heating unit, the crystal is, for an appreciable length of time, at a lower temperature than the walls of the container, due to the poor conducting qualities of the air within the receptacle. These differences of temperature between the crystal element and the receptacle have been found to affect, to a degree at least, the operating properties of the piezo-electric crystal resonator. In accordance with the present invention, a temperature regulating system is provided which entirely avoids such temperature differences.

It is also known that piezo-electric crystals in the state of oscillation vibrate vigorously and tend to move from their normal position between their electrodes. Inasmuch as the frequency of oscillation of the crystal is affected by its position between its electrodes it is a desideratum that for good frequency stability the position of the crystal be fixed. This tendency of the crystal to move while vibrating is appreciably diminished, if not entirely overcome, in accordance with one feature of this invention which prevents movement of the crystal from its fixed position. This feature resides in the apparatus employed to hold the crystal in fixed relation with respect to its electrodes.

A further feature lies in the apparatus for actuating the heater control relay. This apparatus utilizes the flow of fluids possessing electrical

and heat conducting properties for opening and closing the circuit to the control relay.

In accordance with this invention, the temperature of a piezo-electric crystal resonator is controlled by utilizing one wall of a metallic block 5 as one of the crystal electrodes. A fluid, contained within the block, is caused to control a circuit device by the variations in temperature of the crystal and block, in turn, controlling the flow of current in the apparatus.

One advantage of the present invention is that there is no substantial difference in temperature between the piezo-electric crystal resonator and the walls of the cell or block. This is due to the fact that one of the electrodes of the frequency 15 control device forms an integral part of the cell wall.

Another advantage of this invention is that the temperature of the system can fall materially far below or rise far above the operating temperature at which the system is designed to function without destroying the calibration of the control element.

Other objects, features and advantages will appear in a subsequent detailed disclosure.

Referring to the drawing:

Fig. 1 illustrates diagrammatically a particular circuit embodiment of this invention for controlling the temperature of a piezo-electric crystal resonator;

Fig. 2 is a plan view partly in the section of a crystal resonator and cell taken along the line 2—2 of Fig. 1. This view illustrates the manner in which the crystal is held firmly in position by the prongs extending inwardly from the crystal 35 housing.

In Fig. 1 is shown a piezo-electric crystal resonator mounted directly on a metallic block 1, which is filled with a non-electrical conducting fluid 2. This fluid may be any suitable nonconducting 40 fluid such as castor oil, kerosene and ether, which are herein mentioned only as being illustrative of any fluid which may be used. Metallic fins 3 extend downwardly from one surface of the block 1 into the fluid 2. A large surface of contact is 45 thus provided between the block and the fluid which tends to prevent any appreciable difference in temperature between these two elements. For heating the unit a heater wire 4 is provided which connects with a source of current supply. This 50 heater wire is supported by the metallic fins 3 and insulated therefrom. The heating element or wire may comprise any means known to the art and is not limited to the exact form shown in the drawing. In the use of the particular em- 55

means of cock 6 and tube 5. Chamber 52 is provided with an opening 53 leading directly to the atmosphere. The purpose of this opening will 10 be described later. This chamber is filled with the fluid 2 to the level 11. Chamber 51 connected to chamber 52 by tubing is provided with a heavy electrical conducting fluid such as mercury, which is adapted to complete an electrical circuit 15 between metallic plates 9 and 10, extending through the glass walls, whenever the heavy fluid makes contact with both plates simultaneously. The level of the mercury being indicated at 54 in chamber 51 and 55 in the chamber 50, a position which is just slightly below the upper contact in chamber 51. A relay circuit extends from metallic plates 9 and 10 to the box indicated at 20 41. Circuit 41 may comprise any type of circuit known to the art such as shown in the drawing 25 which is adapted, when electrical conducting path across plates 9 and 10 is closed, to open the source of electrical supply connected to the heater wire 4 and, whenever the circuit across the plates 9 and 10 is opened, to again connect the source 30 of current supply to the heater element.

The cock 6 is adapted to connect the inside of block 1 directly with chambers 50 and 52 as illustrated in the drawing or when rotated 90 degrees clockwise, to connect the inside of the block 35 with chamber 50 only.

The operation of the temperature control system will now be described. Assuming that it is desired to maintain the temperature of the crystal resonator and cell at 50 degrees C., the cock 40 6 will be set in the position shown in the drawing by the operator. An electric current will flow through the heater wire 4 and will cause nonelectrical conducting fluid 2 to be heated, in turn heating block 1. As fluid 2 expands, it will flow 45 through tubes 5 and 12 into the glass chamber 52 causing the level 11 of the fluid in this chamber to rise. The fluid 2 will not flow into the chamber 53 from block 1 at this time due to the balance of pressure during this initial expansion. As 50 soon as the temperature of the block has reached the desired value, which is in this particular embodiment 50 degrees C., the operator will rotate the cock 6 clockwise 90 degrees, thus closing chamber 52 to the inside of block 1 and the cock 55 51 will remain in this position. The storage space in chambers 50, 51 and 52 maintains the calibration and obviates the necessity of again setting cock 6. Chamber 50 will now be the only chamber communicating directly with block 1 through 60 tube 5 and will receive any further expansion in the fluid 2. The flow of the liquid into chamber 50 from tube 5 will alter the mercury levels and thus force the mercury out of chamber 50 and into tube 13 to chamber 51, causing the mercury 65 in chamber 51 to rise and make contact with metallic plate 9. The mercury being already in contact with metallic plate 10 will complete a circuit to operate the relay apparatus in box 41, which will now function to cut off the current in heater 70 wire 4, thus preventing any further rise in temperature of the fluid 2 in block 1. The current flowing between plates 9 and 10 need only be very small to obtain satisfactory operation of the relay apparatus in box 41. Due to radiation from 75 the block, the temperature will now begin to fall,

this process will continue repeating itself. Due to the great heat storage in the fluid 2, the actual temperature change required to turn the heat on and off again is so small as to have a negligible effect on the frequency of the oscillations of the crystal.

Returning now to the condition mentioned above wherein the relay apparatus in 41 functions to disconnect the source of current supply 15 to the heater element 4, the atmospheric pressure through opening 53 in chamber 52 acting upon the fluid 2 will force the mercury in chamber 51 to be lowered and to open the circuit between metallic plates 9 and 10 as soon as the 20 temperature of the fluid in block 1 begins to fall. The mercury will now be forced into chamber 50. At this time it should be noted that the volumes of the chambers are such that mercury cannot be forced entirely out of chamber 51 nor can 25 the fluid 2 be sucked entirely out of chamber 50 and the volume of chamber 52 is such that the level 11 of fluid 2 cannot drop below the top of the mouth of tube 12 by a drop in block temperature due to power failure or similar causes. 30 On the other hand, if for any reason, the control circuit in box 41 fails to function properly and the temperature of the block 1 continues to rise above the operating temperature—in this case 50 degrees C.—the volume of the mercury in 35 chamber 50 is such that a reasonable factor of safety—say 10 degrees rise—(60 degrees C.) will not cause fluid 2 to be forced past the mercury, thus destroying the calibration. Chamber 52 is made sufficiently large so that there will not be 40 any overflow through the opening 53 in the top of the chamber caused by an abnormal rise in temperature.

In actual practice there will always be a slight difference in temperature between block 1 and 45 the fluid 2 due to the heat resistance between these two elements. This temperature will vary with the amount of heat which flows from the fluid 2 to the block 1. Should the atmospheric temperature fall, the heat dissipated from block 50 1 will increase and the temperature difference between fluid 2 and block 1 will increase due to the increased heat flow. Thus, there is a tendency for the temperature of block 1 to drop with a drop in atmospheric temperature. This tendency is, however, compensated by the effect of the change in atmospheric temperature on the volume of fluid 2 in chamber 50 and the mercury in chambers 50 and 51. This compensating action 55 will now be described.

As the temperature of the atmosphere falls, the temperature of the fluid and mercury in chambers 50 and 51 also falls, causing the fluid to contract. This contraction causes the mercury in chamber 51 to become lowered, having the same effect as though the fluid inside block 1 was cooling and the volume decreasing. In order to have the mercury again make contact with plate 9 the temperature of the fluid 2 within block 1 must be raised an amount such that the corresponding expansion of the fluid in block 1 will be equal to the contraction of the fluid in chamber 50. This will cause an amount of heat to be supplied which compensates for the increased temperature difference between the fluid 70 75

2 and block 1. One method of obtaining the desired relation between the volume of the fluid in chamber 50 and the volume of the fluid in block 1 is to vary the amount of radiating surface 5 between block 1 and the atmosphere by using suitable heat insulators. A further method of obtaining the desired relation which may be employed involves changing the area of contact between fluid 2 and block 1 by changing the 10 number or size of fins 3. In this manner the temperature of the crystal cell may be held at the 50 degrees C. level to within one hundredth or two hundredths of a degree C.

A particular feature which aids in maintaining 15 the crystal cell at a constant temperature is the raised boss on block 1 forming the lower electrode 22 of the cell. This boss may be plated with a special conducting metal such as silver and is ground to a smooth finish. Secured to lower 20 electrode 22 in such a manner that its temperature is also regulated, is a metallic ring 33 forming part of the crystal holder. Located within this ring is another ring 34 for holding the crystal in its proper position. This ring 34 is designed 25 to fit tightly against the inner surface of ring 33 and is held firmly in place by rods 29 and 30. Two parallel prongs 52, 52 are provided on each side of ring 34 and extend inwardly toward 30 the center for holding the crystal 21 in place. These prongs may be cut off to any desired length 35 so that the crystal will be restrained from movement except within very narrow limits. Spacers 26, 27 and 28, which are made of fused quartz and are ground to a required thickness, are provided 40 for spacing the upper electrodes 23 and 24 the desired amount above electrode 22. These spacers may be provided with screws which fit into electrode 22. In this embodiment the upper electrode is divided into two concentric electrodes 45 23 and 24, which are mounted on a disk of insulated material 25 such as bakelite. These electrodes may either be screwed into the disk or if the disk is made of a material such as Isolantite, the electrodes 23 and 24 may be fused to it. The 50 surfaces of these electrodes are ground very accurately to a true plane surface with the faces plated with a special conducting metal such as silver. Disk 25 is designed to have a slightly smaller diameter than the inner diameter of ring 55 33 with segments cut at two points to permit insertion of rods 29 and 30.

This upper electrode assemblage is adapted to bear on rods 29 and 30 and to be held securely 55 in place by the pressure of spring 31. A plurality of springs 32 pressing down upon the top of the assemblage are utilized to force it against quartz spacers 26, 27 and 28. These springs may be rotated out of the way if it is desired to remove the upper electrode assemblage. Although one 60 spring 32 is shown, it is to be understood that there may be as many such springs as are considered desirable. Terminals 36, 37 and 38 provide electrical connection from the crystal cell to other parts of the system not shown.

65 Although the temperature control system has been described in connection with a piezo-electric crystal resonator, it is to be understood that this form of temperature control is not limited in scope thereto, but may be employed for the control of the temperature of any other object.

What is claimed is:

1. A temperature regulating device having a container composed substantially of metal, a heating element within the body of said container, an external source of power for heating 75

said element, at least one of the walls of said container being in intimate thermal contact with one of the electrodes of a crystal resonator, a non-conducting fluid surrounding said heating element, said non-conducting fluid being adapted 5 to expand and contract in accordance with variations in temperature of said crystal resonator, an insulating container located and supported outside said metallic container, said insulating container having three separate chambers which 10 are in fluid communication with each other and also said metallic container, a conducting fluid retained within at least one chamber of said insulating container, the non-conducting fluid normally located within the other two chambers of 15 said insulating container, means for controlling the flow of said fluids within said chambers, said second mentioned fluid being responsive to the actions of said first mentioned fluid for controlling 20 the source of power supplied to said heating element.

2. A temperature regulating device having a container composed substantially of metal, a heating element within the body of said container, an external source of power for heating 25 said element, at least one of the walls of said container being in intimate thermal contact with one of the electrodes of a crystal resonator, a non-conducting fluid surrounding said heating element, said non-conducting fluid being adapted 30 to expand and contract in accordance with variations in temperature of said crystal resonator, a conducting fluid retained within an insulating container and supported outside of said metallic container by an upward extending communicat- 35 ing member having a valve for controlling the flow of said fluids, said second mentioned fluid being responsive to the actions of said first mentioned fluid for controlling the source of power supplied to said heating element. 40

3. A temperature regulating device having a container composed substantially of metal, a heating element within the body of said container, an external source of power for heating said element, at least one of the walls of said 45 container being in intimate thermal contact with one of the electrodes of a crystal resonator, a non-conducting fluid surrounding said heating element, said non-conducting fluid being adapted to expand and contract in accordance with variation in temperature of said crystal resonator, a conducting fluid retained within a plurality of insulating chambers and supported outside of said metallic container by an upward extending 50 communicating member having means for controlling the flow of said fluids, said second mentioned fluid being responsive to the actions of said first mentioned fluid for controlling the source of power supplied to said heating element. 55

4. A temperature regulating device having a container composed substantially of metal, a heating element within the body of said container, an external source of power for heating said element, at least one of the walls of said container being in intimate thermal contact with 65 one of the electrodes of a crystal resonator, a non-conducting fluid surrounding said heating element, said non-conducting fluid being adapted to expand and contract in accordance with variations in temperature of said crystal resonator, 70 a conducting fluid retained within a plurality of insulating chambers, at least one of said chambers having metallic contacts and supported outside said metallic container by an upward extending communicating member having means 75

for controlling the flow of said fluid, said second mentioned fluid being responsive to the actions of said first mentioned fluid and cooperating with said contacts for controlling the source of power supplied to said heating element.

5. A temperature regulating device having a container composed substantially of metal, a heating element within the body of said container, an external source of power for heating 10 said element, at least one of the walls of said container being in intimate thermal contact with one of the electrodes of a crystal resonator, a non-conducting fluid surrounding said heating element, said non-conducting fluid being adapted 15 to expand and contract in accordance with variations in temperature of said crystal resonator, a conducting fluid retained within a plurality of insulating chambers having upper and lower communicating members, at least one of said chambers having metallic contacts and supported outside 20 said metallic container by an upward extending communicating member having means for controlling the flow of said fluids, said second mentioned fluid being responsive to the actions 25 of said first mentioned fluid and cooperating with said contacts for controlling the source of power supplied to said heating element.

6. A temperature regulating device having a container composed substantially of metal, a heating 30 unit within said container, an external source of power for heating said unit, at least one of the walls of said container being in direct thermal contact with an electrode of a piezo-electric crystal resonator, said electrode located on a raised 35 boss of a metallic hollow block having contained therein said heating unit, a non-conducting fluid surrounding said heating unit, an insulating chamber on the top of said hollow block and adjacent said boss, said insulating chamber having

fluid communication with said metallic hollow block, a conducting fluid within said chamber, an external relay circuit connected with said heating unit, a pair of electrical contacts located in said chamber, so that when the non-conducting 5 fluid expands within the hollow block it will cause the conducting fluid in the chamber to rise so as to complete the said relay circuit and cut off the current supply in said heating unit.

7. A temperature regulating device having a 10 container composed substantially of metal, a heating element within the body of said container, an external source of power for heating said element, at least one of the walls of said container being in intimate thermal contact with one of 15 the electrodes of a crystal resonator, said wall which is in intimate contact with said crystal resonator having a plurality of depending metallic fins, insulating means for supporting said heating element by said fins, a non-conducting 20 fluid surrounding said heating element, said non-conducting fluid being adapted to expand and contract in accordance with variations in temperature of said crystal resonator, an insulating container located and supported outside said 25 metallic container, said insulating container having three separate chambers which are in fluid communication with each other and also said metallic container, a conducting fluid retained within at least one chamber of said insulating 30 container, the non-conducting fluid normally located within the other two chambers of said insulating container, means for controlling the flow of said fluids within said chambers, said second mentioned fluid being responsive to the actions 35 of said first mentioned fluid for controlling the source of power supplied to said heating element.
